UNITED STATES PATENT OFFICE.

HUBERT TILLMAN ANTON DICKOPF, OF MONTCLAIR, NEW JERSEY.

PHOTOGRAPHIC-SPOTTING-BRUSH MOISTENER.

1,372,341.

Specification of Letters Patent. Patented Mar. 22, 1921.

Application filed August 20, 1919. Serial No. 318,843.

To all whom it may concern:

Be it known that I, HUBERT T. A. DICKOPF, a citizen of the United States, and a resident of Montclair, in the county of 5 Essex and State of New Jersey, have invented new and useful Improvements in Photographic - Spotting - Brush Moisteners, of which the following is a specification.

This invention relates in general to 10 moistening devices, and more particularly to a moistening device for photographic spotting brushes.

The objects of the invention are to provide a moistening device of the character 15 described whereby a moistening surface is constantly maintained with a proper degree of moisture for photographic spotting brushes; to provide such a device comprising a fountain or receptacle for moistening 20 fluid from which the moistening surface is constantly supplied by capillary action; to provide a construction whereby excessive moisture in the moistening surface is prevented; to obtain a device of this character 25 by means of which a photographic spotting brush may be properly moistened by mere contact with the moistening surface; to provide a moistening surface which will not injure the brush; to provide a bodily yielding 30 moistening surface whereby the proper contact of the brush therewith is assured; to provide a moistening device in which the brush can be washed without disturbing or moving the moistening surface, and to obtain 35 other results and advantages as may be brought out by the following description.

Referring to the accompanying drawing, in which like numerals of reference indicate the same parts throughout the several 40 views,

Figure 1 is a perspective view of a photographic spotting brush moistening device constructed in accordance with my invention, and

Fig. 2 is a vertical longitudinal sectional view through the same.

Specifically describing the embodiment of the invention illustrated by the drawings, the reference character 1 designates a 50 water-tight receptacle adapted to contain any suitable moistening fluid, such as water, the said receptacle being provided with a cover 2. The said cover 2 is provided with a pair of transversely extending substantially parallel slots 3 through which is inserted a suitable strip of absorbent material

4. This strip 4 is preferably conventional blotting paper, although any other substantially stiff but flexible absorbent material might be used. The ends of the strip 4 are 60 inserted through the slots 3 from the outside of the cover, and depend into the moistening fluid in the receptacle 1, the portion of the strip 4 between the slots 3 outside of the cover being arched upwardly 65 and spaced from the cover 2.

In the use of the device the moistening fluid in the receptacle 1 travels through the strip 4 of absorbent material by capillary action, so as to moisten the strip for substantially its whole length, and when it is desired to moisten a photographic spotting brush the point of the brush is merely touched upon the outer surface of the strip 4, whereupon the moisture in the strip is 75 conveyed at the point of the brush. Only very slight moisture is required on photographic spotting brushes, and it is quite important that excessive moisture be avoided, and through my invention the 80 strip 4 is constantly maintained with the proper amount of moisture necessary to moisten a photographic spotting brush. The flexibility of the strip 4 and its engagement with the edges of the slots 3 maintain the same spaced from the cover 2 so that the exposed portion of the strip cannot become saturated with the moistening fluid as would be the case were the exposed portion of the strip allowed to contact with 90 and rest upon the cover 2. The arched relation of the strip 4 to the cover 2 also allows circulation of air under the strip so as to allow evaporation of the fluid in the strip and maintain the same at a constant degree 95 of moisture. This arched arrangement of the strip 4 also provides for bodily yielding of the strip 4 so as to regulate the degree of pressure of the point of the brush upon the moistening surface, so that injury to the 100 brush and undue moistening thereof is prevented.

The cover 2 may also be provided with an opening 5 adjacent one end of the strip 4 through which the brush may be inserted 105 into the fluid in the receptacle 1 for the purpose of washing the brush, and this opening 5 eliminates the necessity of a separate receptacle for washing the brush, and also provides means for replenishing the 110 supply of fluid without removing the cover 2. After washing the brush through the

opening 5 most of the fluid can be drained therefrom on the edges of the opening, after which the point of the brush may be rubbed over the depending end of the absorbent strip 4 or drawn along from the opening 5 over the exposed portion of the strip 4, whereupon the strip absorbs the excess moisture in the brush and leaves the proper degree of moisture therein. Obviously, 10 when the strip 4 of absorbent material becomes worn out or too dirty for further use it can be easily and quickly replaced by simply pulling the old strip from the slots 3 and inserting another strip in a similar 15 manner. The frictional engagement of the strip 4 with the edges of the slots 3 will maintain the strip 4 in any desired position relative to the cover 2 of the receptacle 1, and the oblique passage of the strip 4 through the slots 3 will always maintain the strip in an arched and spaced relation with the cover 2.

While I have illustrated and described one possible embodiment of my invention, it 25 will be obvious that many modifications and changes can be made in the construction thereof by those skilled in the art without departing from the spirit and scope of the invention, and I do not desire to be limited 30 in the use of my invention except as required by the following claims when construed in the light of the prior art.

Having thus described the invention, what I claim is:

35 1. In a device of the character described, the combination of a receptacle to receive moistening fluid, a cover for said receptacle, and an absorbent element having a portion thereof extending through said cover into the said fluid and another portion thereof exposed exteriorly of said receptacle, said exposed portion being freely spaced from the said cover.

40 2. In a device of the character described, the combination of a receptacle to receive

moistening fluid, a cover for said receptacle, and an absorbent element having a portion thereof extending through said cover into the said fluid, said absorbent element contacting with said cover at spaced points in the length of said element.

3. In a device of the character described, the combination of a receptacle to receive moistening fluid, a cover for said receptacle, and an absorbent element having a portion thereof extending through said cover into the said fluid and another portion thereof exposed exteriorly of said receptacle, said absorbent element being supported on said cover at points on opposite ends of said exposed portion, and the said exposed portion being freely spaced from said receptacle.

4. In a device of the character described, the combination of a receptacle to receive moistening fluid, and an absorbent element mounted upon the top of said receptacle and having a portion thereof arranged exteriorly of the receptacle and freely spaced from the top thereof while another portion of said absorbent element is submerged in said fluid.

5. In a device of the character described, the combination of a receptacle to contain a moistening fluid, the top of said receptacle having a pair of spaced slots therein, and a strip of absorbent material having its ends inserted through said slots into the fluid in the receptacle and the portion thereof between said slots arched upwardly and freely spaced from said top of the receptacle.

In testimony whereof I have hereunto set my hand in presence of two subscribing witnesses.

May 8, 1919.

HUBERT TILLMAN ANTON DICKOPF.
